UNITED STATES PATENT OFFICE.

DAVID E. HIPOLITO, OF LOS ANGELES, CALIFORNIA; HAZEL C. HIPOLITO, OF LOS ANGELES, CALIFORNIA, ADMINISTRATRIX OF SAID DAVID E. HIPOLITO, DECEASED, ASSIGNOR TO HERSELF, INDIVIDUALLY.

WINDOW-FIXTURE.

1,123,742.

Specification of Letters Patent.

Patented Jan. 5, 1915.

Application filed December 17, 1907. Serial No. 406,954.

To all whom it may concern:

Be it known that I, DAVID EDWARD HIPOLITO, a citizen of the United States, residing at Los Angeles, in the county of Los Angeles and State of California, have invented 5 a new and useful Window-Fixture, of which the following is a specification.

An object of the invention is to provide a simple device that can be sold to the trade 10 ready for application by a mechanic who can select or make the wooden parts for the window, and which device can, by such mechanic, be applied to such wooden parts, and which device, when so applied will afford strong and reliable frictional means to hold the window sash in place, will allow 15 the same to tilt when required, and will yieldingly hold it from tilting, except upon application of requisite force.

20 The invention comprises a pair of rubber plates of light, strong and novel construction pivotally connected together and adapted to hold between them a tongue or weather strip that may be so constructed 25 and applied as to close the joint between two faces that are pivotally connected together.

20 The invention comprises a new article of manufacture and the combination and parts 30 hereinafter described and claimed.

Various objects and advantages may appear from the subjoined detailed description.

The accompanying drawings illustrate 35 the invention.

Figure 1 is a fragmental view partly sectioned illustrating the fixture as applied in practical use. Fig. 2 is a perspective view of the article of manufacture to be sold to 40 the trade, comprising the fixture plates and connection, arranged as the same will be delivered to the trade, and omitting the springs. Fig. 3 is a longitudinal section of the device shown in Fig. 2 with springs in 45 place. Fig. 4 is an end view of the same with springs in section. Fig. 5 is a cross section of the fixture as applied in a window, x^5 — x^5 , Fig. 1, indicates the line of section. Figs. 6 and 7 are face views of the 50 respective rub plates detached. Fig. 8 is an enlarged fragmental detail showing clearly the connection between the bolt and channeled rub-plate.

The rub-plate 1 is pressed from sheet

metal and comprises metal forming three 55 sides of a square and producing the channel 4 and the perforated attaching plates 17 extending outwardly from the channel. The rub-plate 2 is pressed from sheet metal and has a longitudinal groove 5 in opposition to the channel 4, said groove being a segment of a circle in cross-section; and the perforated attaching plates 17 extending outwardly from the groove.

The attaching plates 17 of the rub-plate 1 65 and the attaching plates 17 of the rub-plate 2 are substantially identical, and in use these attaching plates rub together. A bolt 3 is inserted through a central opening in the rub-plate 2 and screw-seated in a central 70 opening 6 in the rub-plate 1 and held adjustably in place by a jam-nut 7. The leaf-spring 8 is placed in the channel 4 upon the bolt 3, and a similar leaf-spring 9 is placed upon the bolt 3 outside of the rub-plate 2. 75

The fixture comprises the parts above enumerated as adapted to be manufactured and placed on the market for the purpose of providing a reversible window with a weatherproof joint; a pair of said fixtures 80 being applied to each reversible sash.

10 designates a sash.

11 designates a stile of the sash, the same being deeply channelled, as shown at 12, to receive the deeply channelled rub-plate 1. 85

13 is a slightly grooved member in the form of a strip to provide a runner or shoe for the sash. The grooved rub-plate 2 is seated in said slightly grooved member. The channels of the stile and the groove of 90 the strip correspond in depth to the channel of the rub-plate 1 and the groove of the rub-plate respectively secured thereto.

14 is a tongue or weather strip yieldingly mounted in the channel 4 and adapted to be 95 spring-pressed by means of the spring 8 and, where required by auxiliary springs 8' into the shallow groove 5.

The spring 9 on the sash runner or shoe strip, is applied between the bolt head 15, 100 and the outside strip or runner, 13, so that the strip is yieldingly forced toward the stile at the same time that the tongue or weather strip is yieldingly forced toward the strip. By this means a constant pressure is applied to hold the rub-plates together, and also to hold the tongue or weather strip 14 and strip 13 together. 105

The tongue has a rounded engaging face 16 to pass out of the shallow groove 5 without jamming whenever the sash is turned relatively to the strip or shoe 13.

5 The rub-plates are each provided with perforated attaching plates 17, having perforations 18, to receive screws 20 for fastening the rub-plates to the respective members as 11 and 13 which the fixture is intended to secure together. In the form shown in the drawings the central perforation 6 of the channelled rub-plate is provided with screw threads 21, and the degree of friction between the rub-plates may be varied by 10 loosening and tightening the bolt 3, and then the adjustment may be maintained by setting the jam-nut 7.

20 In practical use the reversible window is held against free pivotal movement by the friction of the rub-plates which may be adjusted as above detailed to any desired degree of frictional resistance, and in addition to such resistance the resistance of the spring pressed tongue or weather strip helps 25 to hold the window sash firmly in place in the window frame 22 which is grooved in the usual way, to receive the members 13 and allow the same to slide up and down.

30 The plates are of practically the same area after being bent up and are of greater length than width and the perforations 18 by which they are to be fastened to the members that are to be united are spaced apart a greater distance than the width of 35 the plates, so that when the plates are turned crosswise upon each other access to the perforations is afforded on each side of the plates. The space between the perforations 18 at the opposite ends is somewhat 40 greater than the thickness of the members to be united, so that when the plates have been pivoted together they can be turned crosswise to each other and then applied respectively to the members to be united 45 and screws inserted through the perforations and into such members.

50 The rub-plates are channelled for a two-fold purpose, the channel construction serving to permit the use of very light material 55 which can be readily stamped into the form and can be sold at a minimum price; and in the second place, the channels serve the purpose of accommodating the weather strip to make a tight joint. It is not necessary, however, in every instance that a weather strip shall be used, the main feature of the invention being the novel form of the rub-plates whereby their lightness, cheapness and strength are secured.

60 By making the rub-plates of the channelled form and providing them with attaching plates extending outwardly from the channels and adapted to rub against each other great strength and a degree of 65 resiliency is secured with comparatively

light material and the rub-plates are adapted for use with or without the weather strip. Appropriate friction can be provided for by adjusting the nut 7 before the plate 1 is screwed to the sash. The nut 75 engaging the bottom of the channelled plate meets with a measurably resilient resistance as will be understood by reference to Fig. 4 so as to maintain a satisfactory frictional contact in spite of the wear and without frequent adjustments.

80 Important features of the foregoing construction that should be particularly noted as being of great advantage are the channels in the rub-plates, one of said channels being curved, a weather strip designed to seat in said curved channel and substantially fitting from side to side of the other channel so that it will work smoothly in said channel, a bolt adjustably pivoting the two rub-plates together, and a leaf spring mounted on the bolt between the bottom of said other channel and the weather strip and designed to press at its 85 ends against the weather strip, the value 90 of this construction being that the weather strip is thus pressed by the leaf spring at two widely separated points, one on each side of the bolt, so that when the weather strip swings around the axis of the bolt, the 95 weather strip will not tend to cant out of true parallelism with the grooved member 13.

95 What I claim is:—

100 1. A window fixture comprising means 100 forming a channel adapted to receive a weather strip and a spring, attaching plates extending outwardly from the sides of the channel, a rub-plate having a longitudinal 105 groove in opposition to the channel and having attaching plates at the sides of the groove in opposition to the first attaching plates, a bolt connecting the two rub-plates together, a spring upon the bolt outside 110 of the grooved rub-plate, and a spring upon the bolt in the channel.

115 2. In a window, means forming a channel adapted to receive a weather strip and a spring, attaching plates extending outwardly from the sides of the channel and forming a rub-plate; a second rub-plate having a longitudinal groove in opposition to the channel and having attaching plates at the sides of the groove in opposition to the first attaching plates, a bolt inserted 120 through the centers of the rub-plates, a runner upon the outer end of the bolt against the second rub-plate, a weather strip upon the bolt in the channel against the inner face of the second rub-plate, a spring upon the bolt in the channel against the weather strip, and a second spring upon the bolt against the outer face of the runner.

125 3. A fixture for pivotally connecting two members together, said fixtures consisting 130

of two rub-plates, one of which is formed with a deep channel having straight parallel side-walls to form a guide for a weather strip and the other of which plates is arched 5 across the channel and adapted to seat a rounded side of the weather strip; both of said rub-plates being provided with corresponding flanges the flanges of one plate engaging those of the other plates; said 10 flanges being perforated to receive fasteners for fastening the rub-plates to separate

members; the arch and the floor of the channel being perforated to receive a bolt; and a bolt in pivotal relation to the arch and in fixed relation to the channel floor. 15

In testimony whereof I have hereunto set my hand at Los Angeles, Cal., this 5th day of December, 1907.

D. E. HIPOLITO.
